UNITED STATES PATENT OFFICE

106,022

DESIGN FOR A COMBINED LAMP AND RADIO RECEIVING SET

Daniel J. Crowley, Grosse Pointe, Mich.

Application November 9, 1936, Serial No. 65,806

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Combined Lamp and Radio Receiving Set, of which the following is a specification, reference being had therein to the accompanying drawing, forming a part thereof, wherein; my new design of combined lamp and radio receiving set is illustrated by a perspective view.

The design of combined lamp and radio receiving set is symmetrical about its vertical axis

in that the side of the set opposite to the side shown in the drawing is the same in appearance, with the exception that the opening exposing the graduated dial is omitted.

The characteristic feature of the present design resides in the tuning element for a radio receiving set shown substantially in the mid-section of the pedestal.

I claim:

The ornamental design for a combined lamp and radio receiving set substantially as shown and described.

DANIEL J. CROWLEY.
